LOOM

Eric S. Wessborg and William J. Morrison, Saginaw, Mich., assignors to The State of Michigan as represented by the Attorney General

Application February 7, 1938, Serial No. 189,158

11 Claims. (Cl. 139—33)

This invention relates to hand operated looms and the improvement pertains more particularly to means interposed between the beater and the harness frames whereby all thread arrangements for developing the pattern in the finished weave are made without any visual supervision by the operator.

The general type of hand loom to which our improvement is adapted to be applied is well known in the weaving art.

Earlier looms provided for raising and lowering the warp threads in a predetermined sequence so as to form two lines between which the weft threads were passed. It picked or placed weft threads between the divided warp threads, and it beat or struck each weft thread into its appropriate position in the fabric. The warp thread was held taut and was delivered as the weaving proceeded, and the cloth as manufactured was drawn away. The fabric was stretched widthwise in order to prevent the edge threads of a warp from injuring the reed or comb of the beater.

The warp threads were raised and lowered by vertically movable harness frames to form the two lines or shed between which the weft thread was passed. The shuttle was driven through this shed, carrying the weft thread with it, and the beating or consolidating of the weave was done by the reed when pulled forward with the beater bar.

Intermittently driven rollers took up the cloth, and a spring-tensioned drag, applied to the warp beam, regulated the let-off and warp tension.

The warp threads were passed in pairs through spaces between the vertical wires of the reed to keep them in line. The reed also determined the closeness of the warp threads and guided the shuttle from side to side.

In earlier days it was customary to selectively place the threads by working foot treadles that actuated the respective harness frames, and by working the shuttle and the beater by hand. That operation was slow and complicated, and required the operator's constant attention to place the threads properly for a given pattern.

More recently, attempts have been made to eliminate the foot treadles and to perform automatic harness shifting by direct cam actions. Such looms could not make a rug with a pattern or design.

Our improvement obviates all the difficulties above mentioned as being associated with typical hand looms of the old art.

A general object of this invention is to provide

use of blind persons whereby their daily output can be enormously increased over that produced by ordinary hand loom work, and the work can be done with greater comfort and less fatigue; and especially is the improvement an outstanding one because of its capacity for unlimited changes of pattern in the product, on a production scale.

A more specific object is to provide a novel harness selecting device that converts an ordinary hand loom into a dependable semi-automatic weaving machine adapted for use by blind persons or by relatively unskilled operators in making woven fabrics of various patterns and colors at a commercial rate of production, and without defects.

A further new and useful feature of this invention is an improved and simplified mechanism by which the beater is operatively connected to the harness selecting device, the purpose being to insure forceful and positive actions of the selector and sure release of certain of the harness frames at each full stroke of the beater. This intermediate or connecting mechanism is so simplified that a blind person can perform all the manipulations necessary in weaving with full confidence that no mistakes in pattern composition can occur because of lack of visual watchfulness.

A further object is to provide a selector having mechanism interconnecting it with the beater and so ruggedly constructed as to withstand continuous hard usage without getting out of order, yet capable of being readjusted to compensate for wear or misalignment.

The principal devices organized in the example of a loom embodying our claimed invention, in a preferred form selected for purposes of this description, may be enumerated briefly as follows:

(1) A series of conventional harness frames capable of rising and falling vertically, each having an upright rod projecting from the middle of its upper edge, there being a shoulder on each rod;

(2) A series of levers equal in number to the rods and each having a spring-actuated latch positioned to get under the shoulder on the corresponding rod when the rod and the harness frame suspended therefrom are in raised position and allowed to gravitate freely;

(3) A tripping device adapted to release such latches in predetermined sequence, and characterized by a series of tappets arranged on a carrier to which is imparted stepwise movement by which two or more tappets of the series are po-

sitioned operatively in relation to corresponding levers;

(4) A snap-action striker arranged upon being released to impinge simultaneously on all tappets thus positioned; thereby releasing together the latches of corresponding harness frames, which drop;

(5) Mechanical interconnections between the aforesaid tappet carrier and the beater of the loom, such that near the extremity of each movement of the beater in a direction toward the operator the following operations are performed in sequence:

- (a) The raising of all previously dropped harness frames and their free suspension,
- (b) The raising of the snap-action striker,
- (c) The moving of the carrier so as to bring the required number of tappets into operative position,
- (d) The temporary locking of the carrier against undesired movement,
- (e) Immediately thereafter, and near the end of travel of the beater, release of the snap-action striker and its resultant impingement upon the required tappets,
- (f) Finally, releasing the lifters that raised the harness frames, whereby the selector apparatus is restored to its original position.

With the foregoing objects in view and certain others to appear later in the specifications, the invention in such preferred embodiment comprises the devices and arrangements which will now be described. That description will be followed by disclosure of another and modified embodiment. Both will be included in certain of the appended claims.

Fig. 1 is a diagrammatic side view showing the loom framework, the beater, and the location of the harness frame selector, and the mechanical connections of the beater with the frame-raising device and with the harness selecting devices.

Fig. 2 is a front view of the upper part of the framework with the selector, as seen from the right-hand side, Fig. 1.

Fig. 3 is a side view of the selector mechanism.

Fig. 3a is a similar but fragmentary view showing some of the parts in locked position.

Fig. 4 is a rear end view of the parts shown in Fig. 3 with part of the housing removed.

Fig. 5 is a top plan view of the parts shown in Fig. 3.

Fig. 6 is a transverse section on line 6-6 of Fig. 3.

Fig. 7 is a longitudinal sectional view of the lower part of the interconnecting mechanism between the beater and the harness frames, and between the beater and the harness frame selector.

Fig. 8 is a part sectional view, taken in the direction of the arrow, of the parts shown in Fig. 7.

Fig. 9 is a cross sectional view on the line 9-9 of Fig. 7.

For purposes of description, a hand loom having four harness frames is shown. Each harness frame has an upright bar D and each bar has latching and releasing means E. The frame-raising mechanism is actuated by beater A to lift two projecting ends B of the frames, Fig. 2. This frame-raising mechanism is in duplicate, only the left-hand set being shown in Fig. 1, and designated by letter C.

As in conventional hand looms, the weave pattern is determined by the order in which pre-selected harness frames are released and dropped.

Orderly arrangement of the various threads in

the weave is attained automatically by the selector mechanism, detailed in Figs. 3 to 6 and designated in general by letter F.

Selector F comprises the following elements, viz. a latch for each bar D, a carrier having tappets thereon, a beater-actuated mechanism for imparting stepwise movement to the carrier, a striker whereby two or more tappets are caused to release in unison two or more corresponding harness frame bars D.

The carrier may be a conveyor of any suitable construction, such as a plate, a disk, a link chain, or, as is illustrated here, it may be a cylindrical drum-like rotor 1 rotatable in peripheral end bearings 2 which are provided in supporting members 3 and 4.

The tappets are mounted in spaced relation on the rotor 1. As shown in Figs. 3 and 6, which illustrate the rotor as organized to make a diamond pattern in the finished article, twelve longitudinal rows of holes are used in which tappets are slidingly mounted. Each longitudinal row 6 has as many holes as there are harness frames, namely in this instance, four. All tappets 5 are interchangeable in the various holes and are kept in place by their enlarged heads 7 and by removable fasteners such as cotter pins 8. There are two tappets in each row of holes. The specific arrangement of the two tappets in the row is determined by the desired dropping sequence of the harness frames, caused by releasing latches 9 from notches 10 of the upright bars D. Other patterns can be developed at will by appropriately rearranging the tappets on the rotor, or by substituting other rotors with different numbers of tappets differently arranged.

Each latch 9 tends to enter a notch 10 in the upright bar D. Latch 9 is on a suitable lever, preferably an L-lever 11, which is pivoted at 12 to a fixed support.

When the horizontal arm of any lever 11 is depressed counter to the action of a spring 13 a corresponding latch 9 is released and the corresponding harness frame drops.

Figs. 3, 4, and 5 show mechanisms worked by the beater A for advancing the rotor 1 stepwise, so as to bring two selected tappets, 5, into position adjacent the horizontal arms of two out of four of the L-levers 11.

The tappets 5 are loose in their holes 6 and their heads 7 slide upon the upright sloping ends 14 of the horizontal arms of L-levers 11, thus retracting the tappets into the rotor.

A slide bar 16, Fig. 3, moves toward the right during its principal working stroke, being actuated by the beater A, through the frame-raising mechanisms C, Fig. 1. A pawl 17 pivoted to bar 16 engages a ratchet notch 15 on the rotor 1 and revolves it one-twelfth of a revolution at each operation, thus placing two or more tappets 5 of a longitudinal row in line with corresponding L-levers 11, as previously described.

A snap-action striker 18 is raised and released by slide bar 16 so as to impinge simultaneously upon the several tappets 5 thus positioned. When 18 strikes it causes all tappets 5 of a given row to release the proper latches 9 from their upright bars D and drop the corresponding harness frames.

Striker 18, as is shown in Figs. 3 and 5, projects endwise into the drum-like rotor 1 and has up-and-down movement. It is mounted on an arm 19 which is pivoted at 20 to a fixed support, being normally urged downwardly by a spring 21.

To prevent the rotor from over-running its

destined station a chock 22 on slide bar 16 is engaged by one of the peripheral ratchet notches 15 and blocks any further rotation of rotor 1, as is shown in Fig. 3a. A detent 23 is employed to prevent back lash of rotor 1. While the rotor is thus held against undesirable movement in either direction, the striker 18 is released and delivers its blow on the two tappets as just described.

10 A cam 24 on arm 19 is located in the path of travel of a spring-sustained trigger 25 which is pivotally mounted on slide bar 16. As the trigger 25 passes under the cam 24 in the direction of the arrow it raises the striker 18, tensioning the spring 21. When the trigger 25 passes the right-hand end of the cam 24 the striker 18 snaps down. When trigger 25 returns with the reverse movement of slide bar 16 its sustaining spring 26 allows it to fold down so as to pass under cam 24 without lifting the striker 18.

15 It will now be apparent that at each complete stroke of the slide bar 16 to the right in Fig. 3, the pawl 17 which is normally raised by a spring 27, Fig. 3, engages a ratchet notch 15 of the rotor 1 and pushes the latter around one-twelfth of a revolution, bringing two tappets, 5, into line with two corresponding L-levers 11. Striker 18 thereupon hits both tappets simultaneously and thus actuates the latches 9 to drop the corresponding harness frames.

20 When the harness frames drop, their weight drives the vertically slideable bar 34, Fig. 1, downward, and this bar, through suitable lug and collar connections with rod 39, returns the selector slide bar 16 to its original position, shown in Fig. 3.

The striker 18, after delivering its blow, stays down and so holds latch 9 away from bar D until again raised on the next cycle of operations.

25 The striker 18 can impinge on the tappets 5 only when the beater A is moving toward the operator and has almost completed its forward stroke. The beater A, while in that zone has no further effect upon the selector mechanism F after the release of latches 9. This allows the operator to use the beater as many times as he may desire while it is in its "near" position, for driving each weft thread into the cloth without any risk of inadvertently actuating the selector mechanism.

30 The interconnecting mechanism C, by which the beater is operatively connected to the harness frames and is also connected to the selector F, will now be described.

35 Referring to Figs. 1, 7, 8, and 9, it is seen that beater A has connected to it an arm 28 equipped with a turn buckle 29 by which the length of the arm can be adjusted to compensate for wear or for structural deformations caused by racking the frame.

40 The lower end of arm 28, Fig. 7, is offset and carries a pair of rollers 30. The offset portion rests on a leaf spring 31 which has a tendency to urge rollers 30 toward the left and thus keep them in position to travel upwardly along the left-hand faces of a pair of upright ribs 32 which are part of the housing 33. The rollers 30 will travel up to the tops of the ribs 32 on the pull movement of the beater, and then shift to the right, and on the push movement of the beater they roll down along the right-hand faces of the ribs until the end of arm 28 contacts spring 31.

45 It is now evident that repeated pulling and thrusting movements of the beater A throughout its maximum range of movement will cause

rollers 30 to repeatedly travel up one face of the ribs 32 and then down the other face. Shortly after commencing its upward travel the offset portion of arm 28 carrying the rollers 30 rises from spring 31 and begins to lift a vertical bar 34 which, by its enlarged upper end 35, lifts all of the dropped frames B.

50 Means for operating the selector slide bar 16 is shown in Figs. 1 and 2. The ends of bar 16 are connected by means of horizontal rods 36, levers 37, 38, and vertical rods 39 with the respective sets of frame raising mechanisms located at each side of the loom framework.

55 Each vertical rod 39 passes through an apertured lug 40 on the harness frame lifting bar 34; and collars 41, 42 are fixed to the selector rod 39 above and below the lugs 40. A cushioning spring 43 surrounds the rod 39 above the lug 40.

60 Each pull movement of the beater A toward the operator moves lug 40 up and by engaging spring 43 against collar 41 the rod 39 and the slide bar 16 are moved and the selector mechanism is actuated, in the manner and for the purposes described.

65 When bar 16 is clear to the right, Fig. 2, the rollers 30 will have arrived at the top of guide ribs 32 and the harness frame rails B will be at the highest point of their upward travel. The rollers 30 now pass across the tops of the ribs 32, Fig. 7, and out from under the bar 34. The bar 34 drops to its original starting point under its own weight and that of the harnesses not engaged by latches 9. The rollers 30 then pass down along the backs of the ribs 32 without any further effect on the frame lifting mechanism of the selector.

70 The foregoing description relates to our preferred embodiment of the inventive concept, and for commercial purposes, especially in the capability of the apparatus to produce an unlimited number of patterns and designs of work and also in some mechanical respects, it is the most desirable of several possible designs.

75 In some cases, however, it is deemed advisable to provide a harness frame selecting apparatus with a less number of parts, although not capable of producing such a variety of work. Such an embodiment of the invention may be made by simply omitting the striker 18 with its arm 28 and cam 24 and also omitting the trigger 25 and its spring 26. The tappets are in this case projected to their outward position and there fastened, or they may be made an integral part of the rotor 1 by welding or otherwise.

80 When such a rotor is given a stepwise movement the rigid tappets will operate by wiping action on the inclines 14 of the levers 11 and thereby will release the latches 9. In all other respects the action of the machine will be the same as that described in the foregoing specification.

85 It will be understood that in the preferred form, Figs. 3 and 5, the tappets 5 are slideable in rotor 1, whereas in the modified form here referred to they are in effect integral with the rotor 1. However, both forms will for convenience be designated herein by the term "tappets" and it will be so understood.

90 The alternative design in question is limited in its capacity for producing different patterns by the space occupied by the projecting tappets in relation to the lever 11, whereas with the movable tappets there is practically no commercial limit to the capacity of the machine, and furthermore, the machine can be repeatedly changed from producing one pattern to the production of a

different pattern. The movable tappet, however, has another important advantage in that the only parts subjected to any wear in the tripping action of the selector are the cam 24 and trigger 25.

5 These parts are easily replaceable.

Looms equipped with our improvement have furnished remunerative employment for blind persons who, although possessing manual skill were not able to master the rather intricate technique of operating a hand loom, the learning of which involved following a memorized thread pattern combination.

With a loom equipped according to our invention, wherein the pattern combinations can 15 be mechanically incorporated in the selecting mechanism by a seeing person before weaving is commenced, the thread sequences do not require any attention or thought by the blind weaver. He merely attends to the threading of the 20 loom, traces out and ties occasional broken threads, and works the beater back and forth without risk of spoiling goods by mistaken arrangement of warp threads. If anything goes wrong in the normal operation of the selector, 25 or elsewhere in the machine the characteristic sound of the several working parts changes and thus immediate notice is given to the operator.

Having thus described our invention, what we claim and desire to secure by Letters Patent is:

30 1. In a loom, the combination, with a beater and a series of vertically movable harness frames and mechanical intercommunications actuated by the beater for lifting all of the harness frames, of means for selecting and dropping certain of the harness frames while retaining others in raised position, said selecting and dropping means comprising a carrier mechanism including a rotatable hollow drum adapted to be actuated stepwise by the beater during each cycle of its operation, and 40 having selector elements comprising tappets individually movable on said drum being interchangeable thereon from operative to inoperative position at the will of the operator and according to the weave of the pattern desired to be 45 produced, and adapted to cause certain of the frames to be dropped at each operation of the beater.

2. In a loom, the combination, with a beater and a series of vertically movable harness frames and mechanism actuated by the beater for lifting all of the harness frames, of means actuated by said frame-lifting mechanism for selecting and dropping certain of the harness frames while others remain in raised position, said selector means comprising a carrier actuated by the beater and members associated with said carrier and mounted thereon adjustably for projection or retraction therefrom, for selectively releasing at each operation of the beater certain 60 of the frames to be dropped, appropriate to the weave of the pattern desired to be produced.

3. In a loom, the combination, with a beater and a series of vertically movable harness frames and mechanism actuated by the beater for lifting all of the harness frames, of a selector actuated by said mechanism during the lifting of said frames for dropping certain of the frames while permitting others to remain in raised position, said selector comprising a drum to which stepwise rotational movement is imparted by the beater, and tappet members associated with said drum and positioned for selectively actuating, at each cycle of operations of the beater, certain of the harness frames to be dropped,

appropriate to the weave of the pattern being produced.

4. In a loom, the combination, with a beater and a series of harness frames having upright bars and means for holding the same in raised position, of individual releasing means for each bar, a carrier having tappets movably mounted thereon, means imparting to the carrier step-by-step movements for establishing tappets in position to actuate said releasing means, a striker arranged to impinge upon tappets thus established, and mechanical intercommunications operated by the beater and actuating respectively the harness frames, the carrier and the striker, whereby the harness frames are raised, the 15 tappets are positioned, and the striker is released in regular predetermined sequence.

5. In a loom having a beater, the combination, with harness frames capable of rising and falling vertically, each having an upright rod projecting therefrom and formed with a shoulder, of a series of levers equal in number to the rods, each lever having a spring-actuated latch member positioned to get under the shoulder of a corresponding rod when in raised position; means 20 for selectively actuating certain of said latches in predetermined sequence and comprising a series of tappets arranged on a carrier having stepwise movements for positioning certain tappets of the series operatively in relation to 30 corresponding levers; a striker arranged to simultaneously actuate all tappets thus positioned to release latches of corresponding harness frames, and mechanical interconnections between the aforesaid tappet carrier and the 35 beater whereby the following operations are performed in sequence: raising and free suspension of all harness frames, forwarding the carrier to bring certain of the tappets into operative position, and actuation of said tappets by the striker. 40

6. In a loom, a harness frame selector comprising a series of levers each presenting a spring-actuated latch member, tripping means for releasing certain of said latch members in predetermined sequence and comprising a series 45 of individually movable tappets arranged on a carrier, said carrier having stepwise movements for positioning two or more tappets of the series operatively in relation to corresponding levers, and a striker arranged to simultaneously actuate all tappets thus positioned, thereby releasing the latches of corresponding harness frames. 50

7. In a loom, a harness frame selector comprising a series of levers each presenting a latch member, tripping means for releasing certain of 55 said latch members in predetermined sequence and comprising a series of tappet members arranged in rows of various arrangement on a carrier and projecting therefrom, said carrier having stepwise movements for positioning the 60 tappets of successive rows operatively in relation to corresponding levers, and means simultaneously actuating all tappets of a row when thus positioned, for displacing the latches of corresponding harness frames.

8. In a change-pattern loom having a beater and a series of vertically movable harness frames with mechanical intercommunications actuated by the beater for lifting all the frames and having latch devices for releasing certain preselected frames while retaining others in raised position; in combination, a carrier arranged for actuation by the beater stepwise toward said latch device, tappet-like elements individually movable on said carrier and arranged in parallel 70 75

rows, the elements in each row being spaced apart and aligned with corresponding latch devices, the disposition of elements being changeable according to the weave of the pattern desired to be produced; and a snap-action striker actuated to impinge simultaneously upon the tappets of a row while engaged with said latch devices, for releasing the latter.

9. In a change-pattern loom having a beater and a series of vertically movable harness frames with mechanical intercommunications actuated by the beater for lifting all the frames, and having latch devices for releasing certain preselected frames while retaining others in raised position; said loom having, in combination, a carrier arranged for actuation by the beater stepwise toward said latch device and comprising a drum-like rotor having peripheral holes, tappet-like elements slidably mounted in said holes in parallel longitudinal rows, the tappet elements in each row being spaced apart and aligned for engagement with corresponding latch-releasing devices, the said elements being interchangeable in the various holes according to the weave of pattern desired to be produced; and a snap-action striker adapted to impinge simultaneously upon the tappets of a row engaged with said latch devices, for releasing the latter.

ously upon the tappets of a row engaged with said latch devices, for releasing the latter.

10. A selective latch releasing device for loom harness frames comprising a carrier having tappets individually movable thereon and interchangeably arranged in spaced relation in longitudinal rows, means for imparting stepwise movement to said carrier, mechanism actuating said carrier to bring tappets of each row into position against corresponding latches and comprising a longitudinally movable bar operated by the beater of a loom and connected by pawl and ratchet devices to said carrier, a snap action striker actuated by said bar to impinge upon all tappets of a row thus positioned, thereby causing all of that row to release appropriate harness frame latches.

11. A structure as set forth in claim 10 wherein in the carrier comprises a hollow rotatable drum mounted on a fixed support, the periphery of the drum having holes therein, and said tappets being slidably mounted in said holes for lengthwise movement therein in radial direction.

ERIC S. WESSBORG.
